UNITED STATES PATENT OFFICE.

BETTIE ABELL MULLER, OF TACOMA, WASHINGTON.

HOLDER.

Application filed July 10, 1924. Serial No. 725,300.

To all whom it may concern:

Be it known that I, BETTIE A. MULLER, a citizen of the United States, and resident of Tacoma, in the county of Pierce and State of Washington, have invented a new and Improved Holder, of which the following is a full, clear, and exact description.

My invention aims to provide a holder or tongs such as is particularly adapted for use in connection with the manipulation of swabs, pads, and dish rags.

It is a well appreciated fact in connection with the cleaning of dishes, etc. that it is often desirable to use extremely hot water to effect an efficient cleaning of the same, and the use of this hot water spoils the skin of the washer's hands, and in some instances scalds the same.

Thus my present invention aims to provide a holder or gripping device by means of which a wash rag may be held and readily manipulated to effect a thorough cleansing of the dishes without the operator having to immerse the hands in the hot water.

Still another object of this invention is the construction of a device of the character stated embodying the aforementioned virtues, and which will further be capable of being constructed at a nominal figure and incorporate a minimum of operating parts so that any danger of a breakage or jamming of the same will be virtually precluded.

Still further objects of this invention will become apparent in the annexed specification taken in connection with the drawings which latter illustrate one practical embodiment of the same, and in which;

Figure 1 is a face view of a holder embodying my improved construction, and

Figure 2 is a side view thereof.

The essence of my invention consists in the provision of a pair of jaws swingingly secured together at one end and which may be grasped by the hands of the operator, their other or lower ends in turn grasping the pad, swab, etc. and permitting a ready manipulation thereof.

It will be seen in the embodiment illustrated that I preferably form the jaws of relatively stiff wire. Thus one of the jaws includes a pair of wires 5 and 6 which are twisted around each other as at 7 to provide a relatively stiff portion, the lower ends of these wires being bent inwardly as at 8, their upper ends being curved to form ter-

70 minal eyes or loops 9. With a view of embodying the maximum gripping efficiency in the device, the second jaw preferably includes an odd number of wires 10, 11 and 12, the hooked lower ends 8 of which are disposed in staggered relationship with respect to the hooked ends 8 of the wires 5 and 6. Thus upon the lower ends of the jaws being brought to a point at which they will lie adjacent to each other, it will be seen that any intervening piece of material such as a swab, etc. will be gripped with a maximum efficiency and be retained with respect to the jaws.

Finally with a view of retaining the whole in assembled relationship it will be noted that the upper ends of the wires 10, 11 and 12 also terminate in eyes or loops 9 and that a pin 13 extends through all of the loops to form a common pivot point this pin preferably mounting washers 14 exteriorly of the assembled loops which prevent an endwise movement of the looped wires with respect to the pin.

Thus all of the objects set forth in the preamble of this specification have been accomplished and it will readily be appreciated that numerous modifications of structure might readily be resorted to without departing from the scope of my claims; which are;

1. A holder of the character described, including a pair of jaws, each jaw comprising a group of wires, loops formed adjacent the upper ends of said groups, and a pivot pin passing through said loops.

2. A holder of the character described, including a pair of jaws, each jaw comprising a group of wires, said groups being pivotally secured to each other adjacent their upper ends, the wires in each group being twisted around each other to stiffen the jaw.

3. A holder of the character described, including a plurality of jaws, each comprising a group of wires, said groups being movably mounted with respect to each other adjacent their upper ends, the lower ends of the wires of one group being disposed in staggered relationship with respect to the wires of the other group.

4. A holder of the character described, including a pair of jaws, each comprising a group of wires, loops formed adjacent the upper ends of said groups, a pivot pin passing through the loops, the wires in each group being twisted together to provide a

rigid portion, inwardly extending hooked portions adjacent the lower ends of said wires, said hooked portions of each group disposed in staggered relationship to each other.

5. A holder of the character described, including a pair of jaws, each jaw comprising a group of wires, loops formed at the upper ends of the wires of each group, the

loops of one group disposed in staggered relation to the loops of the other group and nesting therewith, the wires of each group twisted together shortly below the loops to stiffen the jaws, and means cooperating with the nested loops to constitute a pivotal connection for the jaws.

BETTIE ABELL MULLER.
